UNITED STATES PATENT OFFICE.

JESSE B. GARBER AND CHARLES CORNWALL, OF SALEM, OHIO, ASSIGNORS TO THE DEMING COMPANY, OF SALEM, OHIO, A CORPORATION OF OHIO.

PUMP.

Application filed September 22, 1923. Serial No. 664,162.

This invention relates to pumps and an essential object of the present invention is to eliminate some of the objectionable features of vertically operable pressure pumps. 5 Some of these objectionable features are, the subjection of the main casting which forms the suction chamber to discharge pressure; the loss of prime when the pump is stopped; the difficulty of packing against 10 leakage from the discharge side of the pump; difficulties of bearing alignment; and the lubrication of all moving parts.

The means for carrying out the above object will hereinafter be set forth in the following description which pertains to the accompanying drawings, and the essential features will be summarized in the claims.

In the drawings, Fig. 1 is a side elevation of a pump embodying our invention, a side cover plate being removed for clearness of 20 illustration; Fig. 2 is a vertical transverse section through the pump; Figs. 3 and 4 are sections taken on the correspondingly numbered lines in Fig. 2; Fig. 5 is a longitudinal section through the upper part of the pump and Fig. 6 is a sectional elevation of 25 a portion of the pump showing the accessibility of the connection between the plunger and the cross head; Fig. 7 is a section similar to the section of Fig. 6 taken on a plane parallel to the drive shaft and wrist pin and showing a modified form of cross head and connections.

The pump illustrated in the drawings, is 30 a triplex pump and comprises a base 10, and an intermediate frame or bearing housing 11, and a discharge housing 13. The base comprises a receptacle which serves as a lubricant chamber for enabling the moving 35 parts to be lubricated by the "splash" system. The base is preferably secured to the intermediate housing as by bolts 17.

The intermediate housing as illustrated 40 has a hollow portion 9 adjacent the lower end thereof which cooperates with the base to provide a lubricant chamber, and has an additional hollow portion 12 in the upper end thereof, forming a suction chamber. The space intermediate these chambers is

occupied partially by guideways 35 for the 50 cross heads, and partly by a cover plate 25 which carries a stuffing box 27 and is adapted to close the lower end of the suction chamber. The hollow portions are shown as connected by upright frame arms 18, adjacent 55 the ends of the pump.

The discharge housing or casing 13 is the only casting which is subjected to discharge pressure. Accordingly, this casting may be made sufficiently heavy to withstand any 60 predetermined pressure, while the castings for the base and intermediate housing need be only sufficiently strong to withstand the weight of the parts and to provide sufficient 65 rigidity for supporting the moving elements. The discharge housing preferably rests upon 70 the top of the intermediate housing and is provided with openings 28 in the top thereof which are arranged to be closed by cover plates 22. To hold this housing in locked 75 position, we have shown cross bars 21 which engage the top of the cover plates 22 and which are adapted to be clamped to the intermediate casing by securing members 20.

To obtain an intermediate housing which 80 is to be subjected only to suction pressure, we employ a cylinder 23 which extends into the suction chamber 12 and is open at the bottom thereof to provide communication with the space intermediate the walls 85 of the cylinder and the walls of the housing. In the preferred form, the cylinder is threaded as at 24 so as to be removably connected to the housing 13. This construction permits the removal of the cylinder whenever 90 the housing 13 is lifted from the housing 11. Moreover, the replacement of the cylinder may be readily effected, while the size thereof may be varied in accordance with 95 the pressure. The inlets to the suction chamber 12 are indicated at 19 as being above the bottom of the cylinder wherefore, the cylinder is always provided with a liquid seal and the loss of prime is prevented.

To permit examination and repair of the 95 valve members without dismantling the entire pump, we have shown a discharge valve 60 of the ball and cage type, as having a

shank 61, which is threaded to engage a correspondingly threaded portion within the cover 22. Thus the discharge valve may be readily removed merely by removal of the plate 22. Suitable packing such as a cup-shaped member 62 is shown in connection with the discharge valve.

The inlet valve indicated at 31 is also shown as the ball and cage type and as being mounted directly within a piston or plunger 10. With this arrangement, both valves are accessible whenever the cover plate 22 is removed. To prevent leakage past the inlet valves, we have provided suitable cup-shaped packing members 32.

To operate the pistons or plungers, we employ piston rods 8, the upper ends of which are attached to the pistons and the lower ends of which are removably connected to the cross heads 16. Each cross head in turn is reciprocated by mechanism mounted within the lower portion of the housing 11. Since the chamber 12 is subjected only to suction pressure, then the packing in the stuffing-box 27 need exert only sufficient pressure on the rod 8 to prevent the entrance of air into the suction chamber. When the pump is inactive however, the packing functions to prevent the leakage of water downwardly along the piston rod.

To prevent leakage into the lubricant chamber, we utilize a flange 37 on the cross-head which serves to collect any leakage water flowing along the rod. Any surplus liquid within the cup-shaped portion of the cross-head may be led away by a conduit 38 into a space within the housing 11 formed by transverse walls 39. A waste or drain conduit 40 may be connected to carry the liquid from the base.

A convenient means for connecting the piston rod to the cross-head is illustrated by a threaded member 33 which engages the rod 8 and abuts a transverse wall 29 in the cross-head. An opening 34 in the cross-head permits the member 33 to be moved relatively to the rod whenever the cross-head is in the uppermost position, as shown in Fig. 6. When the member 33 is removed, then the piston rod and plunger may be lifted out of the cylinder which necessitates merely removal of the cover plate 22.

To operate each cross-head, we have shown a connecting rod 55 which engages a wrist pin 56 in the cross-head and is mounted at the other end on an eccentric drum 54, as shown in Figs. 2, 3 and 6. Each drum is rigidly connected or is integral with a gear 53 which in turn is loosely mounted on a stationary shaft 15. Each gear is shown as driven by a pinion 52 on a drive shaft 50. The shafts 15 and 50 are mounted in bearings 14 and 51 respectively in the housing 11. These bearings are above the plane of separation between the housing and the base

10 and are formed all integral with the intermediate housing 11, wherefore alignment between the shafts and the cross-head is effectively maintained. Moreover, since each gear is rotatably mounted on the shaft 15, 70 and is individually driven by a pinion 52, such gears may be adjusted and positioned relatively to each other to position each eccentric at the proper angle for timing the pump.

In order that all moving parts may be in an enclosed case, we find it desirable to provide closely fitting flat plates 70 and 71 as shown in Fig. 2. These extend across from laterally projecting flanges of the arms 18 80 and may be secured by any suitable form of screws 73 preferably extending through both plates and being provided with wing or thumb nuts 72.

As noted, the base 10 forms an oil chamber, and suitable drainage and venting may be provided by the passage indicated at 67 from which rises a gauge pipe 68 having a cap on its upper end provided with a small opening as shown at 69.

Lubrication of the wrist pins and cross-heads also by the splash system may be facilitated by the use of grooves in the cross-head guides 35, as shown at 80, Fig. 7, terminating in an annular groove 81 limiting the upward splash and flow of the oil. These grooves also communicate with the spaces at the end of the wrist pin which in this form is shown with axial and radial oil passages 82 and 83. In the modification shown in Fig. 7 is illustrated another method of securing the piston rod 8^a to the cross-head 16^a, that is by the use of a lock pin 85 fitted in a transverse hole in the head and engaging the end of the rod, as shown. A plate 90 shown at 90 as covering an opening in the gear housing may be provided if desired to afford convenient access thereto for inspection, adding oil, etc.

The construction above set forth provides a pump wherein the entrance to the cylinder, that is to the suction chamber, is always below the inlet conduit, so that the plungers are at all times submerged in liquid trapped in the chamber below the suction opening and the pump cannot lose the priming. Moreover, the difficulties of disposing of leakage is eliminated while the entrance of leakage into the oil chamber is prevented. A further important characteristic of a pump 110 made in accordance with our invention is the exclusion of discharge pressure on any part of the housing, other than the discharge housing, which is specifically designed to hold the discharge pressure. An advantage 120 of this arrangement is that the main casting may be of light construction while the discharge casting may be varied to suit the pressure for which the pump is designed to operate. A further important feature of 130

this invention is the independent connection between the driving and driven shafts for adjusting the angular position of each driving unit with relation to the adjacent unit, 5 therefore the units employed are interchangeably used on single or multiple plunger pumps.

It will be noted that our construction provides for the simplest possible form of cylinders which may be made of any material described, for the reason that each is a separate tube individually fastened to the discharge chamber.

It will also be seen from the foregoing 15 description that we avoid one of the principal difficulties of an inverted vertical pump, that is, a pump where the working plungers are above the actuating means, which difficulty is namely that the dripping or leaking 20 of the water or other fluid being pumped will follow down the connecting rods and other parts to the oil reservoirs. By our invention the pump is so constructed that; first, leakage is reduced to a minimum by 25 reason of the construction described; and second, any leakage which may occur along the connection rods is entrapped and drained away, protecting the operating mechanism below.

30 Summarizing other advantages resulting from our construction, it will be seen that all moving parts are splash-oiled except the plungers operating in the fluid being pumped. It is convenient to provide all 35 parts in an enclosed case and make all bearings of ample size. The arrangement of each eccentric rigid with its gear but capable of individual adjustment upon the main drive shaft makes possible the setting of the 0 eccentrics and correspondingly the plungers, in any desired relation to each other. It will be noted that the eccentric gears and driving pinions are by our construction mounted 5 on parallel shafts having bearings in the same casting, which is obviously advantageous and which also allows for lubrication 0 from the same splash-oiling system. The main casting including as it does all transverse and vertical bearing members for the 5 moving parts, provides permanent and assured proper alignment, not only for the shafts, but for the cross-heads and plunger members as described. The accessibility to 5 the valves as well as to the other parts proves itself very valuable in the course of years of operation of such pumps.

We claim:—

1. In a pump, the combination with an inlet housing of a discharge housing, a cylinder 0 carried by the discharge housing and projecting into the inlet housing and an inlet passageway in the first housing above the bottom of the cylinder, whereby the priming of the pump may be maintained when the pump is inactive.

2. In a pump, the combination with a suction housing of a discharge housing positioned thereon and having an opening therein, a closure for said opening and a discharge valve depending from said closure. 70

3. In a pump, the combination with a suction housing of a discharge housing positioned thereon and having an opening therein, a closure for said opening, a cylinder within the suction housing and a discharge 75 valve carried by said closure and extending within said cylinder.

4. In a pump, the combination with a pair of casings, one superimposed upon the other, of a cylinder carried by the upper casing and 80 projecting into the lower casing and having the bottom thereof open, an inlet passageway in the lower casing above the entrance to the cylinder, a plunger movable within said cylinder an inlet valve on said 85 plunger, and a discharge valve associated with the upper casing and extending across the upper end of said cylinder.

5. In a pump, the combination with a pair of casings, one superimposed upon the other, of a cylinder carried by the upper casing and projecting into the lower casing so as to be held in spaced relation thereto, a plunger movable within the cylinder, said upper casing having an opening in the top 90 thereof, a closure for said opening, an inlet valve carried by the plunger and a discharge valve carried by said closure, said valves being in vertical alignment to permit access thereto when the closure is removed. 95

6. In a pump, the combination with a pair of casings, one superimposed upon the other, a cylinder carried by the upper casing and projecting into the lower casing so as to be disposed in spaced relation thereto, an inlet 105 passageway in the lower casing, the bottom of said cylinder terminating short of the bottom of the lower casing and also being disposed below said passageway, a plunger operable within said cylinder, an inlet valve 110 mounted on said plunger, the upper casing having an opening opposite said cylinder, a closure for said opening, a discharge valve depending from said closure and projecting into said cylinder, and means engaging the 115 top of said closure for holding the casing in clamped position.

7. In a pump, the combination with a pair of casings, one superimposed on the other, of a cylinder carried by the upper casing and 120 projecting into the lower casing, a cover plate mounted on the upper casing, a discharge valve removably secured to said cover plate and extending within said cylinder, a plunger movable with the cylinder and having an inlet valve mounted thereon, and means within said lower casing for operating said plunger. 125

8. The combination with a pair of casings, one superimposed upon the other, the lower

casing comprising an inlet chamber and the upper casing comprising a discharge chamber, a cylinder in threaded engagement with the discharge casing and projecting within the suction chamber, the discharge casing having an opening opposite the end of the cylinder, a closure for said opening and a discharge valve in threaded engagement with said cover, said valve serving partially as a head for said cylinder. 10

In testimony whereof, we hereunto affix our signatures.

JESSE B. GARBER.
CHARLES CORNWALL.
